UNITED STATES PATENT OFFICE.

FREDERICK W. MARTIN, OF BROOKLYN, NEW YORK, ASSIGNOR TO FRANKLIN RAILWAY SUPPLY COMPANY, A CORPORATION OF DELAWARE.

FURNACE DOOR.

Application filed May 21, 1921. Serial No. 471,410.

To all whom it may concern:

Be it known that I, FREDERICK W. MARTIN, a citizen of the United States, residing at Brooklyn, in the county of Kings and

5 State of New York, have invented certain new and useful Improvements in Furnace Doors, of which the following is a specification.

10 My invention relates to furnace doors, and more especially to the opening and closing action or mechanism of such doors. I aim to make the door arrangement and mechanism simple, rugged, and compact; convenient and reliable in use and operation; and 15 relatively inexpensive to manufacture. How these and other advantages can be secured in connection with the invention will appear from my description hereinafter of the best form of embodiment at present 20 known to me.

The invention is in some respects specifically applicable to fire doors consisting of plates adapted to swing across the door opening,—such as are used especially on 25 steam locomotives,—and I have herein described it with special reference to that use. In my drawings, I have shown the door plate fulcrum on the door frame structure to one side of the door aperture, so that the door plates swing directly upward and downward in opening, respectively, but the door frame structure can equally well be arranged the other way, with the fulcrum above the door aperture, so that the door 30 plates shall swing outward and upward to either side in opening.

In the drawings, Fig. 1 is a front elevation of a furnace door structure and mechanism conveniently embodying my invention, the operating foot lever being partly broken away.

40 Fig. 2 is a similar view of the parts behind the line 2—2 in Fig. 4 with the operating motor cylinder and its mounting plate removed.

Fig. 3 is a view corresponding to Fig. 2, showing the doors open.

Fig. 4 is a side or end elevation, from the left of Fig. 1.

50 Fig. 5 shows a transverse section through the doors and door frame, taken as indicated by the line 5—5 in Fig. 1.

Fig. 6 is a plan view, with certain parts broken away and removed as indicated by 55 the line 6—6 in Fig. 1.

Fig. 7 shows an axial mid-section through the motor cylinder and the pressure-control valve casing, on a larger scale than Figs. 1 to 6.

Fig. 8 shows a horizontal section through 60 the motor cylinder and its mounting plate, taken as indicated by the line 8—8 in Fig. 7.

Fig. 9 is a side elevation of the motor cylinder from the right of Fig. 7, showing 65 the pressure-control valve casing in longitudinal section as indicated by the line 9—9 in Fig. 7, and the check valve 47 open.

Referring to Figs. 1 to 6, it will be seen that the door shown comprises a frame 10 with a door opening 11 therein, and that the door plates or leaves 12, 13 are fulcrumed on this frame at one side of the door opening, by means of pivot studs or bolts 14, 15 that extend through the lateral arm 70 portions 16, 17 of the door plates. The door plates 12, 13 thus swing apart and together, edgewise, across the door opening; and they are interconnected and thus constrained to move in unison by means of a 75 link 18 which operates across the line of their fulcrum 14, 15 during opening and closing movements. When closed, the door plates 12, 13 are held against internal pressure (inside the furnace) by an overhanging lug 19 on the frame 10, which overlaps the free ends of both door plates.

For operating the door plates 12, 13, there is provided a fluid-actuated piston 22, arranged to move crosswise of the door-plates, in the direction of the line of the fulcrum 14, 15. Compactness, simplicity, and economy of space are promoted by locating the path of crosswise movement of the piston 22 inside the fulcrum 14, 15 rather than outside,— 85 i. e., to the side toward the door opening rather than to the side away from it, as here shown. The cylinder 25 for the piston 22 and the control-valve casing 26—in a word, the fixed structure of the fluid-actuated door 90 motor—are mounted on the front of a supporting plate 27 which is itself mounted on the reduced forward ends of the pivot-studs 14, 15 and secured by nuts 28, 29 on said studs. The supporting plate 27 extends inward and downward from the pivot-studs 14, 15, and the crosswise extending door motor 25, 26 is integrally attached to its lower portion. (See Figs. 6 and 8.) Thus the motor cylinder 25 extends in front 100 of the door plates 12, 13.

of the door plate 13, which is permitted to swing back and forth behind it. The initial opening movement of this door plate 13 is in substantially the same general direction 5 as the corresponding movement of the piston 22. The piston 22 is directly connected to the door plate 13 by a link 30, (Figs. 1, 2 and 3) pivoted to the door arm 17 at 31, inside its fulcrum at 15, and pivoted to the 10 cross-head portion 32 of the piston 22 by means of a pin 33 screwed fast in the lower end of the link and extending through a slot 34 in the rear side of the crosshead guide portion 35 of the cylinder 25 and into 15 a corresponding guide slot 36 in the door frame 10. (See Fig. 7.) The operating link connection 30, it will be seen, extends behind the cylinder 25.

The fluid-actuated piston motor 22, 25 20 may preferably operate, primarily, to open the door plates 12, 13, which may normally be closed by gravity. With the arrangement shown, the upper door plate 12 may be cast somewhat heavier than the lower one (or 25 otherwise overweighted) to assure prompt closing; but if the structure be arranged with the pivots 14, 15 above the door opening, this will be unnecessary. Operating fluid under pressure (e. g., air or steam) is con- 30 stantly supplied to the valve cavity in the casing 26; and its entrance above the piston 22 to depress the same and open the furnace door is controlled by the conical valve 37 (see Figs. 7 to 9) seated at 38 at the lower 35 side of the cavity, and constantly urged toward its seat by a helical compression spring 39 above it,—as well as by fluid pressure. The valve 37 is attached to a plunger rod 40 fitting closely and longitudinally mov- 40 able in the base of the casing 26, and the rod and the valve can be raised by upward pressure on the protruding lower end of the latter, as by means of a pedal lever 41 fulcrumed at 42 between lugs 43 on the 45 valve casing 26.

When the control valve 37 is thus raised, the fluid admitted beneath it passes through a passage 44 in the metal of the combined cylinder and valve casings 25, 26 to ports 50 45, 46 leading to the upper end of the cylinder, the latter above the piston 22,—open- 55 ing the check-valve 47 on its way. At the same time that the control valve 37 is raised, the fluid-tight head portion 48 of the rod 40 overtravels and closes the exhaust- 60 port 49 in the valve casing. When the pressure control valve 37 is released and allowed to close again, the exhaust port 49 is opened and the cylinder 25 vented to the atmos- 65 phere. As or after the rising piston 22 overtravels the port 45, the check-valve 47 controlling the port 46 is closed by and entraps the relatively low-pressure fluid remaining in the upper end of the cylinder 25, and this entrapped fluid serves to cushion

the final closing together of the door plates 12, 13.

The movement of the rod 40 that opens the control valve 37 brings into register with the port 50 (leading to the lower end 70 of the cylinder 25 beneath the pis- ton 22) an annular groove 51 in the rod 40 which communicates with the pressure chamber above the valve 37 through holes 52 and 52' and a bore 53 in the rod which bore is plugged at its upper end. The pressure fluid thus admitted to the lower side of the piston 22 cannot over- 75 come the full pressure on the much larger upper side; but when the valve 37 is closed 80 and the upper side of the piston 22 vented, this full pressure fluid at the lower side of the piston 22 is entrapped by the descent of the head 48 across the port 50, and its ex- 85 pansion aids in closing the door plates 12, 13 against the cushion afforded by the entrapped fluid above the piston.

I claim:

1. A furnace door comprising a pair of door plates mounted to swing apart and together, edgewise, across the door opening, a link interconnecting said plates and con- straining them to move in unison which link operates across the line of their fulcra; and a fluid-actuated piston for operating 90 the door arranged to move in the direction of the line of fulcra of the plates and oper- atively connected to one of said plates.

2. A furnace door comprising a pair of door plates mounted to swing apart and to- 100 gether, edgewise, across the door opening, a link interconnecting said plates and con- straining them to move in unison which link operates across the line of their fulcra; and a fluid-actuated piston for opening the door, 105 with a link-connecting it directly to one of said door plates.

3. A furnace door comprising a pair of door plates mounted to swing apart and to- 110 gether, edgewise, across the door opening, and interconnected to move in unison; and a fluid-actuated piston for operating the door arranged to move cross-wise of the door plates inside their fulcra.

4. A furnace door comprising a pair of door plates mounted to swing apart and to- 115 gether, edgewise, across the door opening, and interconnected to move in unison; and a fluid motor for operating the door mounted to permit one of the door plates to swing 120 behind it, inside their fulcra.

5. A furnace door comprising a pair of door plates pivoted to swing apart and to- 125 gether, edgewise, across the door opening; a fluid motor for operating the door mounted and arranged for one of the door plates to swing behind it, and for its piston to move inside their fulcra in substantially the direction of the initial opening movement 130 of one of the door plates; and linkage

means operatively connecting said piston to the door plates, and interconnecting the door plates to swing in unison.

6. A furnace door comprising a pair of door plates mounted to swing apart and together, edgewise, across the door opening, linkage means interconnecting said plates and constraining them to move in unison which linkage means operates across the line of their fulcra; a common overhanging lug for overlapping the free ends of both door plates to hold them against internal pressure when closed; and a fluid motor for operating the door mounted to extend in front of one of the door plates inside their fulcra.

7. A furnace door comprising a pair of door plates mounted to swing apart and together, edgewise, across the door opening; a supporting plate mounted and secured on

the fulcra of said door plates, and extending inward from them; and a fluid-actuated piston motor on the front of said supporting plate extending crosswise of the door plates inside their fulcra, with an operating connection from the piston to one of the door plates inside its fulcrum extending behind said cylinder.

8. A furnace door comprising a pair of door plates mounted to swing apart and together, edgewise, across the door opening, a link interconnecting said plates and constraining them to move in unison which link operates across the line of their fulcra; and a fluid-actuated piston for operating the door.

In testimony whereof, I have hereunto signed my name.

FREDERICK W. MARTIN.
